UNITED STATES PATENT OFFICE.

JULIUS MERMELSTEIN, OF PHILADELPHIA, PENNSYLVANIA.

CLOTHES-SUSPENDING APPARATUS.

1,329,541.

Specification of Letters Patent.

Patented Feb. 3, 1920.

Application filed April 18, 1919. Serial No. 291,020.

To all whom it may concern:

Be it known that I, JULIUS MERMELSTEIN, a citizen of the United States, residing at Philadelphia, in the county of Philadelphia and State of Pennsylvania, have invented 5 certain new and useful Improvements in Clothes-Suspending Apparatus, of which the following is a specification.

One object of my invention is to provide 10 improved apparatus for supporting or suspending clothes so that clothes can be hung thereon in a manner so as to occupy a minimum amount of space.

Another object is to so construct the apparatus of my invention that the part which 15 directly supports the clothes can be raised to such a level that the clothes will be out of the way of persons walking thereunder and for this reason my invention is particularly 20 well adapted for use in residences or the like for supporting washed clothes so that they can readily dry.

A still further object is to so construct the apparatus of my invention that it can be directly attached to the ceiling of a room and 25 so that the clothes-supporting part can be readily raised and lowered.

Another object is to so construct the clothes-supporting part that the clothes will 30 not accidentally become detached therefrom.

A further object is to make my invention of a simple and durable construction and so 35 that it can be easily manufactured and sold at a comparatively low price.

These objects, and other advantageous 40 ends which will be described hereinafter, I attain in the following manner, reference being had to the accompanying drawings in which—

Figure 1 is a side elevation of my invention shown attached to a ceiling or other overhead structure,

Fig. 2 is an end elevation of Fig. 1,

Fig. 3 is a sectional plan view taken on 45 the line 3—3 of Fig. 1,

Fig. 4 is an enlarged fragmentary sectional elevation taken on the line 4—4 of Fig. 2; the central portion being broken away,

Fig. 5 is a transverse section taken on the line 5—5 of Fig. 1,

Fig. 6 is a transverse section taken on the line 6—6 of Fig. 1, and

Fig. 7 is a perspective view of one of a number of pulley-supporting brackets which 55 form a part of my invention.

Referring to the drawings, 8 represents a longitudinally extending beam having a removable top cover plate 9. The beam and cover plate are adapted to be supported by 60 lag bolts 10 to a ceiling 11 or other overhead supporting structure, such for example as shown in Figs. 1 and 2. The beam 8 has a longitudinally extending channel 12 which is closed on its top by the plate 9. Two 65 apertures 13 and 14 extend upwardly from the bottom surface 15 of the beam and communicate with the channel 12 at its opposite ends, as clearly shown in Fig. 4. Two pairs of brackets 16 and 17 are provided and each 70 of the brackets has a recess 18 in its upper surface which permits the brackets to embrace the sides of the beam 8, as clearly shown in Figs. 5 and 6. Each of the brackets 16 and 17 has a flange 19 following 75 the line of the recesses 18 and these flanges 19 permit of the attachment of the respective pairs of brackets 16 and 17 to the beam 8 by bolts 20; the nuts on the upper ends of said bolts being adapted to fit 80 within cavities 21 so that the upper ends of the bolts will be covered by the top plate 9. The brackets of each pair have inwardly extending lips 22 which form a closure at the ends of the brackets for the space between 85 the brackets, as clearly shown in Fig. 3 so that the space between the brackets provides a passageway for raising and suspending ropes, as will hereinafter be more completely described.

90 A pulley block 23 has arms 24 which are secured by screws 25 to the top of the beam 8, said arms being set in recesses cut within said beam at opposite sides of the channel 12, as clearly shown in Figs. 3, 4 and 6 inclusive. The pulley block 23 includes a shaft 26 upon which four pulleys 27, 28, 29 and 30 are rotatably mounted. The pulleys 27, 28, 29 and 30 are positioned directly over the aperture 14 and the brackets 17 100 are positioned under the aperture 14 so that one side of each of said pulleys 27, 28, 29

and 30 is tangent to a plane passing through the space between the pair of brackets 17. Thus it will be understood that ropes passing downwardly from said latter 5 pulleys will pass directly through the space between the pair of brackets 17, as clearly shown in Fig. 4.

Another pulley block 31 has arms 32 which are supported on the top of the beam 8 adjacent the opposite end of the channel 12 and these arms are set in recesses in a manner similar to that described in connection with the arms 24. The pulley block 31 includes a shaft 33 upon which are mounted 15 two pulleys 34 and 35 (see Figs. 3, 4 and 5). The pulleys 34 and 35 are so positioned that ropes passing thereover can extend directly downwardly through the aperture 13 and space between the pair of brackets 16.

20 The brackets 17 form a rotatable support for four pulleys 36, 37, 38 and 39, said pulleys being freely rotatable on shafts 40 which are secured in the pair of brackets 17. Thus the pulleys 36, 37, 38 and 39 are positioned 25 so as to rotate freely in the space between the pair of brackets 17 and serve as supporting and guiding members for two ropes 41 and 42, said ropes also respectively passing upwardly from under the pulleys 37 30 and 38 over the pulleys 28 and 29 and then downwardly through the aperture 14 and are connected to a ring 43, said ring 43 having a hoisting rope 44 attached thereto, as clearly shown in Fig. 2.

35 The brackets 16 also form a support for four shafts 45 (see Fig. 5), said shafts supporting pulleys 46, 47, 48 and 49. These latter mentioned pulleys are in the same arrangement with respect to the brackets 16 as 40 the pulleys 36, 37, 38 and 39 occupy with relation to the brackets 17. Two other ropes 50 and 51 pass over the pulleys 27 and 30 and downwardly through the aperture 14 and between the brackets 16 and respectively pass 45 under the pulleys 47 and 45 and then over the pulleys 46 and 49. The lower ends of the ropes 50 and 51 are provided with snap hooks, such as shown at 52 in Figs. 1 and 2, said snap hooks on the ropes 50 and 51 being secured to eyelets 53 in the opposite ends 50 of bars 54 in a rack 55. The rack 55 includes a longitudinally extending main bar 56 to which the transverse bar 54 is connected, said main bar also supporting an 60 other transversely extending bar 57 to which the lower ends of the ropes 41 and 42 are attached by means of snap hook and eyelet connection similar to that described in connection with the elements 52 and 53. The 65 transversely extending bars 54 and 57 are

spaced apart and the connection with the bars 54 and 57 and their respective supporting ropes 41, 42, 50 and 51 is such that the ropes, in supporting the rack 55, will hang vertical, as is shown in Figs. 1 and 2.

70

The main bar 56 of the rack 55 forms a support for clothes supporting pins 58. These pins 58 extend through holes in the bar 56 and at their opposite ends are split as shown at 59 to permit clothes to be slipped 75 and wedged therein. In other words, the pins 58 are bifurcated and the insertion of clothes or other fabric serves to spread the furcations which thereby firmly hold the clothes to the pins and prevent them from accidentally falling off the pins when the rack is raised and lowered as will be described hereinafter.

80

By arranging the pulleys and ropes as above described, the rack 55 can be raised 85 by pulling on the rope 44 and the rope 44 can be attached to any securing means, such for example as the cleat 60, as shown in Fig. 1 so that the rack can be held in its raised position. Furthermore by making the 90 brackets of the shape as illustrated, the pulleys 37 and 38 and pulleys 47 and 48 can be positioned directly below the respective apertures in the beam and the pulleys 46 and 49, and 36 and 39 will serve to firmly 95 support their respective ropes at a position at opposite sides of the beam so as to permit the ropes to be freely manipulated without chance of entanglement during the raising and lowering operation.

10

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

11

Having thus described my invention, what I claim as new and desire to secure by Letters Patent is:—

1. Apparatus of the character described including a supporting beam having an inclosed channel and apertures communicating with said channel; pulleys positioned within said channel; a clothes-supporting rack; ropes attached to said rack and extending upwardly through said apertures and over the pulleys within said channel, said ropes having portions extending out of said channel whereby the rack can be raised and lowered; brackets secured to said beam and providing a space through which said ropes can pass; and pulleys positioned within the space between said brackets and around which said ropes pass; substantially as described.

1

2. Apparatus of the character described including a supporting beam having a channel therein; pulleys positioned within said

1

channel; a clothes-supporting rack; ropes attached to said rack and extending upwardly and over the pulleys within said channel, said ropes having portions extending out of said channel whereby the rack can be raised and lowered; brackets secured to said beam and providing a space through which said ropes can pass; and pulleys positioned within the space between said brackets and around which said ropes pass, said brackets being made in pairs having oppo-

sitely disposed lips forming a closure for the space between said brackets of each pair; substantially as described.

In testimony whereof I have signed my name to this specification in the presence of two subscribing witnesses.

JULIUS MERMELSTEIN.
